United States Patent Office.

CHARLES H. MILLER, OF BUFFALO, NEW YORK, ASSIGNOR TO CHARLES HARRISON, OF NEW YORK CITY.

Letters Patent No. 71,510, dated November 26, 1867.

IMPROVED VALVE FOR WATER-CLOSETS.

The Schedule referred to in these Letters Patent and making part of the same.

TO ALL WHOM IT MAY CONCERN:

Be it known that I, CHARLES H. MILLER, of the city of Buffalo, county of Erie, and State of New York, have invented an Improved Self-Acting Valve; and I do hereby declare that the following is a full, clear, and exact description thereof, reference being had to the accompanying drawings, making a part of this specification, in which—

Figure I is a longitudinal section of said valve.

Figure II is a longitudinal section of the valve-seat and cylinder, with adjustable piston, by which the movements of the valve are controlled.

Figure III is a cross-section of same on line 1-2 of Fig. II; and

Figure IV is also a cross-section on line 3-4 of Fig. II.

The invention relates to that class of valves usually applied to water-closet basins to admit a definite quantity of water therein after each use, and consists—

First, in governing the action of the valve by an adjustable piston attached to the stem thereof, and working loosely in a cylinder, which, filling with water during the opening of the valve, will permit the closing thereof only after the displacement therefrom of the water by the piston; the adjustment of the piston on the stem regulating the quantity of water which will enter the cylinder, and consequently the time which the valve will remain open for the flow of the water to the basin.

Second, in making the piston-cylinder, which also forms the valve-seat, separate from the valve-casing, so that it and all the working parts may be removed for repairs without disturbing the connection of the casing to the basin and supply-pipe.

Like letters refer to like parts in each of the figures.

A represents the valve-casing, having a projecting shank, A¹, by which it may be fastened to the basin, a water-supply orifice, A², at the bottom, and a discharge-orifice and nozzle, A³, at the side; also, a cylindrical chamber, A⁴, at the top for the reception of the piston-cylinder.

B represents the piston-cylinder, the same being a plain cylindrical shell, open at both ends. When in place, its upper half fits snugly the bore of the chamber A⁴, and its bottom end fits by a grooved joint to a partition-seat, B¹, dividing, in connection with the valve, the supply from the discharge-passage. An enlargement of the chamber A⁴ forms an annular space, A⁵, around the lower half of the cylinder, with which the bore of the cylinder communicates by the row of holes, B², near the lower end thereof. This cylinder may be made a part of the casing, but I prefer to make it separate and removable.

C represents the valve, having its seat formed in the lower end of the cylinder B, its stem, C¹, extending up longitudinally through the cylinder, and projecting through the screw-cap C², by which the chamber is covered. When the valve is opened by a downward push on the valve-stem, a communication between the supply and discharge-orifices is opened for the flow of the water by way of the holes B² in the lower end of the cylinder.

D represents the piston applied to the valve-stem, and fitting loosely in the bore of the cylinder. The valve-stem having a screw-thread cut thereon working in a female thread cut in the piston, so that the piston being prevented from turning by a feather projecting from its periphery into a longitudinal groove in the side of the cylinder, the turning of the valve-stem will raise or lower the piston thereon. The valve-stem is provided with a button or thumb-wheel, D¹, at its upper end, by which it may be easily turned to adjust the piston.

A spiral spring, E, interposed between the valve and a shoulder, E¹, around the supply-orifice, assists the water-head or pressure in seating the valve. A packing-washer, F, is interposed between the screw-cap and the top of the cylinder to prevent leakage, said washer also fitting closely to the valve-stem. The supply and discharge-nozzles are furnished with coupling-nuts, G and H, for the attachment of their respective pipes.

Operation.

The valve is opened by a downward push on the valve-stem, given by means of a lever-pull of common construction, or by connection with the seat-board in a common manner. The distance which the valve will open is regulated by the position of the piston on the valve-stem, the striking of the piston on an inner seat, I, at the

lower end of the cylinder arresting any further downwaad movement. Turning the valve-stem in such direction as to raise the piston thereon and increase the distance between the valve and piston, will evidently increase the distance which the valve may open, while a reverse movement of the piston on the stem will decrease the distance which the valve may open. When the valve is open, the piston will cover the openings b^2 , and prevent any considerable flow of water, but the cylinder above the piston will fill by leakage past the same, so that when the valve is free to rise by the release of the lever-pull or seat-board, its movement will be retarded by the water above the piston, until the same shall be displaced by the piston, escaping from the cylinder by leakage as in filling. The higher the position of the piston on the valve-stem, the greater will be the movement of the valve, and the greater the amount of water entering the cylinder for subsequent displacement, and in consequence the longer will be the time occupied in such displacement, and during which the flow of water through the valve will continue. Small holes, J, are made through the side of the cylinder into the groove, in which the piston works to facilitate the filling of the cylinder. It is evident that however long the valve may remain open, the piston covering the holes b^2 will prevent any considerable flow of water, thus specially adapting the valve for operation with a seat-board. Further, by raising the piston on the valve-stem until it strikes the cap, it may be prevented from closing at all, thus causing it to act as a waste-valve, which will oftentimes prove a great convenience.

All these adjustments of the piston and valve are effected with the utmost readiness by simply turning the valve-stem, as before described. The cylinder, piston, and valve may at any time be removed from the casing by simply unscrewing the cap c^2 , and without disturbing the connection of the casing with the basin or supply pipe. This feature will prove of great convenience and utility when the valve needs cleaning or grinding.

Having thus described my invention, what I claim, and desire to secure by Letters Patent, is—

1. The adjustable piston D, in combination with the valve C and cylinder B, substantially as described.
2. The removable cylinder B, arranged in the body of the faucet, and forming a water-chamber above the piston, for the purpose and substantially as described.

CHARLES H. MILLER.
